UNITED STATES PATENT OFFICE

97,777

DESIGN FOR A LIGHTED ELECTRIC RAZOR

Charles J. Merriam, Winnetka, Ill.

Application February 11, 1935, Serial No. 55,342

Term of patent 14 years

To all whom it may concern:

Be it known that I, Charles J. Merriam, a citizen of the United States, residing at Winnetka, in the county of Cook, in the State of Illinois, have invented a new, original, and ornamental Design for a Lighted Electric Razor, of which the following is a specification, reference being had to the accompanying drawing, forming a part thereof, in which—

Fig. 1 is a side elevation of a lighted electric razor, showing my design;

Fig. 2 is a front elevation; and
Fig. 3 is a top plan view.

The dominant feature of the design resides in the light hoods the contours of which merge into the contour of the razor casing, and which are located one at each side of the casing and near the operating end thereof.

I claim:

The ornamental design for a lighted electric razor substantially as shown and described.

CHARLES J. MERRIAM.
